UNITED STATES PATENT OFFICE.

MORTON HAVENS, JR., OF ALBANY, NEW YORK.

DESIGN FOR A BRANCH BOX FOR INSULATED ELECTRIC WIRES.

No. 39,764.

Specification for Design.

Patented Jan. 12, 1909.

Application filed February 16, 1906. Serial No. 301,509. Term of patent 7 years.

To all whom it may concern:

Be it known that I, MORTON HAVENS, Jr., a citizen of the United States, residing and having my post-office address at No. 79 Chapel street, in the city of Albany, county of Albany, and State of New York, have invented a new, original, and ornamental Design for a Branch Box for Insulated Electric Wires.

In the accompanying drawing, Figure 1 is a perspective view of a branch box for insulated electric wires, embodying my design, and Fig. 2 is a perspective view of said branch box shown as inverted.

This design for branch boxes comprises an elongated body having a cap or closure on

one side so shaped as to constitute a continuation of the lines of the body. The side opposite the closure has rounded ends and sides, and two nipples in line project laterally from the central portion of this elongated body, all of the parts being joined by easy curves.

What I claim is:—

The ornamental design for a branch box for insulated electric wires, substantially as herein shown and described.

MORTON HAVENS, JR.
